UNITED STATES PATENT OFFICE.

MAHLON W. WAMBAUGH, OF GALVESTON, TEXAS.

RAIL-JOINT.

SPECIFICATION forming part of Letters Patent No. 570,618, dated November 3, 1896.

Application filed June 13, 1896. Serial No. 595,452. (No model.)

To all whom it may concern:

Be it known that I, MAHLON W. WAMBAUGH, a citizen of the United States, residing at Galveston, in the county of Galveston and State of Texas, have invented a new and useful Rail-Joint, of which the following is a specification.

The invention relates to improvements in rail-joints.

10 The object of the present invention is to improve the construction of rail-joints and to provide a simple, inexpensive, and efficient device capable of affording a firm and secure support for the abutting ends of rails to maintain their treads in the same horizontal plane and prevent them from being mashed down at the ends, whereby the life of a rail is materially increased and the jars and jolts incident to the passage of the wheels of a train over rough 15 rail-joints are prevented, thereby contributing to the comfort of the travel.

Another object of the invention is to increase the firmness, durability, and efficiency of a railroad-track, and to prevent the fish- 20 plates from being strained by the passage of a train, in a manner similar to the ordinary unsupported fish-plates.

25 The invention consists in the construction and novel combination and arrangement of parts, hereinafter fully described, illustrated in the accompanying drawings, and pointed out in the claims hereto appended.

In the drawings, Figure 1 is a side elevation of a rail-joint constructed in accordance 30 with this invention. Fig. 2 is a transverse sectional view of the same. Fig. 3 is a perspective view of the stationary lower portion or base of the adjustable support. Fig. 4 is a reverse plan view of the same. Fig. 5 is a 35 perspective view of the movable upper portion of the adjustable support, the upper portion being inverted to show the helically-inclined serrated faces. Fig. 6 is a detail sectional view illustrating the construction of 40 the inclined slots of the lugs of the fish-plates.

45 Like numerals of reference designate corresponding parts in all the figures of the drawings.

50 1 1 designate a pair of rails connected together by transverse bolts 2 and angle fish-plates 3, which are located at opposite sides

of the rails and which conform to the configuration of the webs and bottom flanges thereof. The fish-plates are provided at their 55 outer faces, adjacent to their ends, with substantially triangular lugs 4, which have inclined slots 5 for the reception of the ends of depending truss-rods 6.

The slots 5 are oppositely inclined, converging downward, and they are also transversely inclined, extending downward from their mouths, and the ends of the truss-rods, which are arranged in the slots, are provided with heads 7 engaging the outer side faces of the 65 lugs and forming stops. The truss-rods, which are arranged in pairs at opposite sides of the rails, are curved and extend beneath and connect the rails, and they have mounted on them an adjustable supporting-block 8, 70 forming a strut and located directly beneath the ends of the rails. Instead of forming the heads 7 of the truss-rods 6 integral with the latter, the terminals of the truss-rods may be threaded, and nuts may be employed to serve 75 as heads, and may be arranged on the outer inclined faces of the triangular projections 4 similar to the heads 7.

The adjustable supporting-block comprises a stationary lower portion or base 9 and a 80 rotary upper portion 10. The lower portion or base is curved at its lower face and provided with grooves 11, arranged adjacent to its side faces and receiving the lower curved portions of the truss-rods, and the movable upper portion 85 10 is provided with a flat upper face for the reception of the rails. The upper and lower portions 9 and 10 of the adjustable block or strut are provided at their contiguous faces with oppositely-disposed substantially 90 semicircular flanges 12 and 13, tapering throughout their lengths and presenting contiguous helically-inclined faces 14 and 15, which are serrated and adapted to engage each other, whereby the upper and lower sections of the block 8 are retained at any desired 95 adjustment. The flanges 12 and 13 of the upper and lower portions or sections are arranged in the form of a circle, which extends half-way around the block, the reduced portion of one flange being arranged adjacent to the enlarged portion of the other flange of the same portion or section.

100 The upper portion or section 10 is circular

and fits within a circular flange or rim 16 of the lower section or base 9, and when the upper section is in its lowermost position the vertical shoulders 17 of the enlarged ends of 5 the flanges 12 abut against the shoulders 18 of the flanges 13, and by rotating the upper sections 10 its curved flanges are adapted to ride up the helically-inclined surfaces of the lower section or base to increase the height 10 of the strut and to draw the parts of the rail-joint to any desired tension. The upper portion or section 10 is provided with horizontal sockets or holes 19 for the reception of a suitable bar or lever for rotating it.

15 The fish-plates bear against the heads of the rails adjacent to their ends, and are beveled at their terminals at 20 to prevent the end portions of the fish-plates becoming fulcrumed against the heads of the rails when 20 the parts thereof are subjected to the weight of a train, whereby the fish-plates are relieved of much strain and are prevented from being twisted or broken like the ordinary fish-plates, which bear against the edge of the 25 rails throughout their entire length.

It will be seen that the rail-joint is simple and comparatively inexpensive in construction, that it is adapted to be readily applied to any rail, and that it forms a firm and secure support for the ends of rails and will increase the strength and durability of the track. It will also be apparent that it is adapted to maintain the treads of the rails in the same horizontal plane and prevent them 30 from being mashed down by car-wheels, and that it will prevent the jars and jolts incident to a train passing over rough rail-joints. Furthermore, it will be apparent that the tension of the truss-rods may be readily increased 35 from time to time, that no threads are employed in regulating the tension of the truss-rods, and that the serrations of the helically-inclined faces of the upper and lower portions or sections of the adjustable block are 40 adapted to interlock and securely hold the parts at any desired adjustment and prevent them from accidentally slipping when subjected to a heavy strain.

Changes in the form, proportion, and minor 45 details of construction may be resorted to without departing from the principle or sacrificing any of the advantages of this invention.

What I claim is—

50 1. In a rail-joint, the combination with a pair of rails, of fish-plates connecting the rails and provided with lugs having downwardly-converging slots, curved truss-bars depending below the rails, located at opposite sides 55 thereof and provided at their terminals with heads, the ends of the truss-rods being arranged in said slots and the heads engaging the lugs, and an adjustable supporting-block or strut interposed between the rails and the 60 truss-rods and provided at its lower face with

grooves for the reception of the latter, substantially as described.

2. In a rail-joint, the combination with rails, of fish-plates secured to the rails and provided at their outer faces, adjacent to their 65 ends with substantially triangular lugs having transversely-slanted downwardly-converging slots, curved truss-rods disposed in pairs having their ends arranged in the slots and provided with heads engaging the lugs at 70 the outer edges or faces thereof, and an adjustable supporting-block or strut interposed between the rails and the truss-rods and provided at its bottom with grooves receiving the latter, substantially as described.

3. In a rail-joint, the combination with rails and fish-plates, of depending truss-rods connected at their ends with the rails, and an adjustable supporting-block interposed between the truss-rods and the rail and comprising upper and lower portions having curved tapering flanges forming helically-inclined surfaces, one of the portions of the block being movable to cause the inclined surfaces to ride on each other, substantially as and for 85 the purpose described.

4. In a rail-joint, the combination with rails and fish-plates, of depending truss-rods connected at their ends with the rails and an adjustable supporting-block interposed between the rails and the truss-rods and composed of a stationary lower section or base provided with curved tapering flanges forming helically-inclined surfaces, the latter being serrated, and an upper rotary section provided with depending tapering curved flanges forming helically-inclined surfaces serrated similar to said flanges and engaging the inclined faces thereof, substantially as and for 90 the purpose described.

5. In a rail-joint, the combination with rails, of fish-plates secured to the rails and provided with slotted lugs, depending truss-rods arranged at opposite sides of the rails and having their ends interlocked with the slotted lugs, and an adjustable supporting-block comprising a stationary lower section or base mounted on the truss-rods, provided with a circular rim and having opposite semi-circular tapering flanges provided with upper 100 helically-inclined serrated faces, and a circular rotary upper portion fitting within the rim of the lower section or base and provided with depending tapering curved flanges having 105 helically-inclined serrated surfaces engaging 110 those of the stationary section or base, substantially as and for the purpose described.

In testimony that I claim the foregoing as my own I have hereto affixed my signature in the presence of two witnesses.

MAHLON W. WAMBAUGH.
